UNITED STATES PATENT OFFICE.

JAMES H. MANN, JR., OF LITTLE ROCK, ARKANSAS.

VENDING-MACHINE.

1,278,186.

Specification of Letters Patent. Patented Sept. 10, 1918.

Application filed March 9, 1918. Serial No. 221,508.

To all whom it may concern:

Be it known that I, JAMES H. MANN, Jr., citizen of the United States, residing at Little Rock, in the county of Pulaski and State of Arkansas, have invented certain new and useful Improvements in Vending-Machines, of which the following is a specification, reference being had to the accompanying drawings.

10 This invention relates to vending machines and more particularly to certain improvements in a vending machine of that general character shown and described in Patent No. 1,217,616 issued to me February 15 27, 1917.

It is the primary object of the present invention to provide a common locking means for the case lid or cover affording access to the magazine and for the coin receiving cup.

20 It is also an important object of the invention to provide locking means for the coin cup which is entirely contained within the body of the case and to which access cannot be had from the exterior thereof whereby 25 by the removal of the coin cup and rifling of its contents by unauthorized persons is effectually prevented.

And it is a further general object of the invention to improve the patented machine 30 as above stated, and yet maintain the very compact arrangement of the elements as disclosed in the original patent and without increasing the manufacturing cost of the machine to an appreciable extent.

35 With the above and other objects in view my invention consists in the improved combination, construction and relative arrangement of the several parts as will be herein-after more fully described, subsequently 40 claimed and illustrated in the accompanying drawings in which similar reference characters designate corresponding parts throughout the several views and wherein:

45 Figure 1 is an elevation with the front of the case removed and certain of the parts in section, showing the case lid and the coin cup in their locked positions.

Fig. 2 is a side elevation of the magazine 50 case removed and showing in dotted lines, the released position of the locking lever.

Fig. 3 is a detail horizontal section taken on the line 3—3 of Fig. 2.

Fig. 4 is a detail perspective view of the 55 locking lever for the coin cup; and

Fig. 5 is a detail perspective view of the coin cup.

The machine as illustrated in the accompanying drawings, is particularly designed for use in railway cars, theaters, and like places, the machine being mounted between the car windows, or on the backs of the seats. It is therefore essential that the parts of the machine shall be very compactly arranged so that the machine as a whole will be of small dimensions, and will occupy but little space. And it is likewise very desirable, in the use of vending machines in such places that access may be quickly had to the interior of the machine for charging the same with the gum or other commodity and that the coins may be readily removed. This result is attained by means of the present invention, wherein the separate key-actuated lock for the coin cup with which such machines are usually equipped, is eliminated and the coin cup at the bottom of the case and the top or lid at the upper end of the case are simultaneously locked by the manipulation of a single key. The particular mechanism whereby this end is accomplished, I will now proceed to describe in detail.

In the accompanying drawings, 5 designates the outer case of the machine which includes a body and a removable front plate (not shown). At its upper end, the body of the case is equipped with a top or cover 7 hinged to the upper edge of its rear wall. On the inside of this cover a suitable key-actuated lock designated 8 is secured adjacent to one end thereof.

Within the body of the machine case 5 a magazine case designated generally by the numeral 9 is arranged. This case is also stamped from a sheet metal plate and includes the longitudinally extending side walls 10 which are slightly spaced from the opposed side walls of the outer case 5. Upon the rear wall of the magazine case 9 the coin controlled article delivery mechanism is mounted. The specific construction and mounting of the several parts of this mechanism has been made the subject matter of another application for patent, and it will not therefore be herein further described in detail. It will suffice to state that the body of the magazine case 9 is provided at its lower end with a tray or pan indicated at 11 into which the articles are delivered. This pan extends substantially one-half the depth of the machine case 5, and the operating lever 12 for the article delivery mechanism which is mounted upon the rear

wall of the magazine case, projects downwardly below the pan 11 at one end thereof as clearly shown in Fig. 1.

13 designates the coin cup which is likewise stamped from a single sheet metal plate to provide a front wall 14, a relatively short rear wall 15 of appreciably less height than said front wall and a longitudinally extending bottom wall 16. The coins, of course, 10 are received between the front and rear walls 14 and 15 and are collected upon the bottom wall 16. This bottom wall at its ends is formed with upturned flanges 17 for engagement over the side walls of the outer case 5 at their lower ends. The bottom wall 16 of the cup is further provided adjacent one end thereof with a notch or recess to accommodate the operating rod or lever 12. At the relatively opposite end of the cup, the front 20 wall 14 has an angularly disposed lug 18 formed thereon, said lug being located in the plane of the end wall of the cup and above the same to thereby provide a recess or notch indicated at 19.

25 Referring now to Fig. 2 of the drawings, it will be noted that the pan or tray 11 is formed on the lower edge of a vertically disposed plate 20 which extends between the side walls of the magazine case 9 below the 30 delivery plate 21 which constitutes the bottom of the magazine. This delivery plate is mounted for rocking or tilting movement upon a rod or shaft 22 the ends of which extend through apertures in the side walls of 35 the magazine case 9. Upon one of the projecting ends of this rod a lever 23 is loosely mounted for pivotal movement. The lever 23 extends vertically between one side wall of the outer case 5 of the machine and the 40 opposed side wall of the magazine case 9. The lower end of this lever is reduced in width as indicated at 24 and is formed with an angular terminal lug 25 extending inwardly through a slot or opening 26 in the 45 side wall of the magazine case. The lever 23 at its upper end is formed with a laterally and forwardly extending angularly disposed flange 27. This flange extends inwardly over the upper end of the side wall 50 of the case 9; and in spaced relation thereto.

55 In operation, after the machine has been charged or loaded with the gum or other commodity, the coin cup is inserted upwardly into the lower end of the magazine case 9 between the side walls thereof and with the front wall 14 of said cup in contact with the rear face of the vertically disposed wall 20 of the pan or tray 11. The flanges 60 17 at the ends of the cup will frictionally engage the side walls of the case 5 and the recess 19 will be disposed in registering relation with the slot 26 in the side wall of the magazine case 9. It will be understood that the coin cup can only be thus inserted, 65 when the lever 23 is disposed in the dotted

line position seen in Fig. 2. The operator then engages the flange 27 on the upper end of said lever with the thumb and forces the same rearwardly, thus rocking the lever and moving the lug 25 on the lower end thereof 70 into the slot 19 and beneath the lug 18 on the wall of the coin cup. Finally, the lid or cover 7 of the case 5 is closed and a key inserted in the lock 8. The lock bolt indicated at 8' when projected to its locked position will engage at its outer end beneath the flange 27 on the upper end of the lever 23. It will thus be apparent that the lid or cover 7 is securely locked and held in its closed position, and the coin cup 13 is likewise locked within the lower end of the case. In other words the lever 23 constitutes a common keeper element which coacts with means on the coin cup and with the bolt of the lock 8 to lock the case lid or cover and 80 the cup against displacement. It will accordingly be seen that my invention obviates the necessity of equipping the coin cup with a separate key-actuated lock. The machine may, therefore, be recharged and the coins 90 removed from the cup and the machine again locked with the loss of but little time. This saving in time is an important factor when the large number of machines with which a single railway coach may be 95 equipped is considered.

From the foregoing description taken in connection with the accompanying drawings the construction, operation and several advantages of the present invention will be 100 clearly and fully understood. It will be seen that by a very simple addition to the machine as illustrated in my prior patent hereinbefore referred to, I have materially enhanced the utility and serviceability of the 105 original machine. The keeper or locking lever for the coin cup is entirely contained within the outer case 5 so that access cannot by any possibility be had thereto and the lower end of said lever displaced in such 110 manner as to release the coin cup. The cup cannot therefore be removed and the coins extracted by unauthorized parties. Of course, the lock 8 will be of an especial construction, requiring a key of peculiar form 115 for its operation. However, even if one succeeded in operating the lock so that the lid or cover would be opened, the attempt to rifle the coin cup would probably still be frustrated owing to the fact that the person being unacquainted with the construction of the machine would not properly manipulate the lever 23 to release the coin cup. Therefore, after further futile attempts to remove the cup he would probably desist in his efforts. As the several parts of the improvement can be readily stamped from sheet metal it will be appreciated that the additional expense involved in the manufacture 120 of the machine as shown in my prior patent, 125 130

will be comparatively small. It is also to be observed that the dimensions of the original machine remain practically the same so that the machine equipped with the improved lock will occupy but little space, thus rendering the machine particularly desirable for such uses as I have heretofore mentioned.

While I have herein shown and described the preferred form, construction and relative arrangement of the various parts of the device, it is to be understood that the same are susceptible of considerable modification therein and I, therefore, reserve the provision of adopting such legitimate changes as may be clearly embodied within the spirit and scope of the invention as claimed.

Having thus described my invention, what I claim is:—

20 1. In a vending machine, a case, a lid or cover for the upper end of the case equipped with a lock, a coin cup, and a common keeper element to coact with the coin cup and with the lock to lock the lid or cover and the coin cup against movement relative to the machine case.

25 2. In a vending machine, a case, a lid or cover for the upper end of the case equipped with a lock, a coin cup, and means wholly disposed within said case and adapted to coact with the lock on the lid or cover and with said coin cup to lock said lid and the cup against movement relative to the machine case.

30 3. In a vending machine, a case, a lid or cover for the upper end of the case equipped with a lock, a coin cup, and a pivoted lever wholly disposed within the case and coacting with the lock on the lid or cover and 40 with the coin cup to lock said lid and coin cup against movement relative to the machine case.

35 4. In a vending machine, a case, a lid or cover for the upper end of the case equipped with a lock, a coin cup, and a pivoted lever having terminal means respectively coacting with the lock on the lid or cover and with the coin cup to lock said lid and the coin cup against movement relative to the machine case.

40 5. In a vending machine, a case having a closure, a coin cup, and means common to both the closure and the coin cup and inaccessible from the exterior of said case to lock the closure and coin cup against movement relative to the case.

45 6. In a vending machine, an outer case having a lid or cover on its upper end and a lock therefor, a magazine case arranged within the outer case and having its side walls spaced from the opposed walls of the outer case, a coin cup removably engaged between the side walls of the magazine case

at their lower ends, and means mounted between one side wall of the outer case and the opposed side wall of the magazine case adapted to coact with the lock for said lid or cover and with said coin cup to lock said lid and the coin cup against movement.

5 7. In a vending machine, an outer case having a lid or cover on its upper end and a lock therefor, a magazine case arranged within the outer case and having its side walls spaced from the opposed walls of the outer case, a coin cup removably engaged between the side walls of the magazine case at their lower ends, and a pivoted lever arranged between one side wall of the outer case and the opposed wall of the magazine case and having terminal means to respectively coact with the lock for the lid and with said coin cup to lock said lid and coin cup against movement.

7. In a vending machine, a case, a rectilinearly movable coin cup mounted in said case, a manually operable locking element inaccessible from the exterior of the case having means on one end to coact with the coin cup and lock the same against movement with respect to the case, and means coacting with the other end of said element to hold the same against movement from its locking position.

8. In a vending machine, a case, a coin cup movably mounted within the case, a pivoted lever wholly contained within said case and having means on one end to coact with the coin cup and lock said cup against movement with respect to the case, and means coacting with the opposite end of said lever to hold said lever against movement from its locking position.

9. In a vending machine, a case, a coin cup movably mounted within the case, a pivoted lever wholly contained within said case and having means on one end to coact with the coin cup and lock said cup against movement with respect to the case, and means coacting with the opposite end of said lever to hold said lever against movement from its locking position.

10. In a vending machine, an outer case having a lid or cover, a magazine case disposed within the outer case, a coin cup removably engaged in the magazine case, and means on the magazine case to coact with said cup and with means on said lid to thereby lock the cup against removal and lock the lid in its closed position.

11. In a vending machine, an outer case having a lid or cover, a magazine case arranged within the outer case, a coin cup adapted to be disposed in one end of the magazine case, and a lever carried by the magazine case having means on one end to coact with the coin cup and lock said cup against removal, and having means on its other end to coact with means on the lid and lock said lid in its closed position.

115 In testimony whereof I hereunto affix my signature in the presence of two witnesses.
